UNITED STATES PATENT OFFICE.

RICHARD PERRY, OF DUNN, ILLINOIS, ASSIGNOR OF SIX-SEVENTHS TO DAVID PERRY AND WILLIAM T. PERRY, OF BETHANY, BENJAMIN F. PERRY, OF TODD'S POINT, AND MOSES H. PERRY AND SAMUEL B. PERRY, OF DECATUR, ILLINOIS, AND MARION S. PERRY, OF STRATTON, NEBRASKA.

CAR-COUPING.

SPECIFICATION forming part of Letters Patent No. 352,569, dated November 16, 1886.

Application filed April 15, 1886. Serial No. 198,941. (No model.)

To all whom it may concern:

Be it known that I, RICHARD PERRY, of Dunn, in the county of Moultrie and State of Illinois, have invented certain new and useful 5 Improvements in Car-Couplings, of which the following is a specification.

The object of my invention is to provide a draw-head and latch that will ordinarily hold a coupling-link inclined slightly upward while a coupling is being made, and that will permit a material horizontal deflection in said link; and it is also my object to provide means whereby the latch may be readily raised and automatically held clear of the link.

15 In the drawings accompanying and forming a part of this specification, Figure 1 is a perspective view of an end of a car, showing my device in position thereon. Fig. 2 is an elevation of the device used to hold the coupling-link out of operation. Fig. 3 is a longitudinal vertical section of my draw-head.

a, b, and c represent the levers with which my coupling is operated.

d represents a series of radial arms, pivoted 25 to the end of the car above the draw-head and connected by means of suitable rods with levers *a b c*, respectively.

e is a pulley located between arms *d* and the draw-head.

30 *f* is a chain that connects the arms *d* with the latch of the draw-head, lug *d'* forming a suitable point of attachment.

g is the draw-head, having link recess *g'* and diminished opening *g''*.

35 *h* represents a latch pivoted in a slot in the draw-head, and provided with horizontal surface *h'* and vertical surface *h''* in the relative positions shown. The outer end of the latch conforms in contour to the mouth of the draw-head, and the angle formed by surfaces *h'* and *h''* is located slightly in the rear of the smallest diameter of throat *g''*, in order that the front end of the link may be slightly elevated by pressure from the latch.

40 45 The recess *g'* is enlarged, as indicated, in order that the outer end of the link may be inclined downward to accommodate low coup-

lings, and in order that a coupling may be readily made without forcing the end of the link against the inner surface of the recess. 50

When the arms *d* are in the position shown in Fig. 1, the chain *f* permits the latch to rest on the link. When the arms *d* are in the position shown in Fig. 2, the latch is raised clear of the interior of the draw-head. In the first- 55 mentioned position the weight of the latch makes its position stable, and in the last-mentioned position the connection of the chain with the arms is carried past the vertical center and the weight of the latch is again utilized 60 in making the position secure.

If, under any circumstances, the weight of the latch should be insufficient to secure it in its different positions, a spring of necessary strength may be used to assist the depression. 65

By the use of my device a car may be readily and effectively coupled and uncoupled from the side or top of the same, so avoiding the necessity of exposing the operator to danger of being crushed between the cars, and cars of 70 differing heights may be coupled together without bent links.

The weight of the latch on the link presses the inner end of the same downward and causes a consequent elevation in its outer end. This 75 elevation should be such as to carry the link toward the center of the mouth of a coupling of medium height, and in case of a variation in the height of the coupling the link will become deflected either upward or downward by 80 the inclined mouth of the draw-head and accommodate itself to the different elevation. In effecting this result the enlarged recess of the draw-head and the pivoting peculiarity of the latch are both utilized. 85

I claim as new and desire to secure by Letters Patent—

1. In draw-heads for car-couplings, the conformable link-guide herein set forth, consisting in the combination of head *g*, having recess *g'* and diminished throat *g''*, and latch *h*, having horizontal under surface, *h'*, normally resting in recess *g'* on a line approximately horizontal with the lower surface of the throat,

and also having a catch, h'' , slightly in the rear of the narrowest portion of the throat, as and for the purpose set forth.

2. Radial arms d , having vertical rotation approximating a quarter-revolution, lug d' , so located on arms d that the motion of said arms will carry the lug from a position approximately horizontal with the pivot of the arms to a position above and slightly past the vertical of said pivot, a chain running over a

guide-pulley and connecting the arms with a latch in the draw-head, and readily-accessible levers connected with the arms, all in combination, as and for the purpose set forth.

In testimony whereof I sign my name in the 15 presence of two subscribing witnesses.

RICHARD PERRY.
